UNITED STATES PATENT OFFICE.

CHARLES P. MADSEN, OF CHICAGO, ILLINOIS, ASSIGNOR TO THE MICHIGAN STOVE COMPANY, A CORPORATION OF MICHIGAN.

ELECTRIC FLAT-IRON.

1,099,988.

Specification of Letters Patent. Patented June 16, 1914.

Application filed September 26, 1912. Serial No. 722,416.

To all whom it may concern:

Be it known that I, CHARLES P. MADSEN, a citizen of the United States of America, and a resident of Chicago, county of Cook, 5 and State of Illinois, have invented certain new and useful Improvements in Electric Flat-Irons, of which the following is a specification.

It is a well known fact that where the 10 windings for electric heating elements are connected in multiple, a smaller sized wire can be used than where the element is made up of a single winding, or where windings are connected in series. It is also known 15 that the heat emissivity rate of resistance material is increased by pressure. I have also discovered that the working capacity or ability to dissipate or to generate and to convert electric energy into heat energy at 20 high temperatures is much greater in smaller wires than in large ones. In constructing heating elements for use in electric heating devices of the pressure plate system of construction, I take advantage of 25 these facts by using relatively small conductors arranged with two or more coils in multiple and thereby gain the advantage of requiring not only a smaller mass of wire to do a given quantity of work, but also 30 find it easier and more convenient to arrange for the various mechanical connections.

The main objects of this invention are therefore to provide an improved form and 35 construction of heating elements adapted for use in electric heating devices of various designs; to provide an improved winding of resistance material whereby resistance material of smaller size and capacity 40 may be used than would otherwise be possible; to provide improved means for making electrical connections between the resistance windings and the electrical conductors; to provide improved means for connecting 45 the windings of the heating element whereby they are securely held in their relative position and whereby they are adapted to be conveniently handled; to provide an improved form of insulation for the heating 50 element; and to provide an improved element of this kind particularly adapted for use in electrical heating devices of the pressure plate or flat surfaced type.

A heating element constructed according to this invention is illustrated in the accompanying drawings as applied to a flat iron of triangular shape, but it will be understood that it is equally adapted to be used with other electrically heated devices such as hot plates, disk heaters, serving trays, etc., 60 either of rectangular, square, circular or other form.

In the drawings—Figure 1 is a side elevation, partly sectional, of a flat iron equipped with a heating element constructed according to this invention. Fig. 2 is a plan view of the heating element. Fig. 3 is an enlarged fragmentary sectional detail taken on the line A—A of Fig. 2. Fig. 4 is an enlarged fragmentary sectional detail 70 taken on the line B—B of Fig. 2.

In the construction shown in the drawings, the heating element is formed of two coils of resistance material 1 in the form of ribbon. The ribbon is wound on the cards 75 or strips 2 of insulating material which may be of any suitable material, herein shown as mica, the windings terminating at the ends of the cards. The windings of the heating element are secured in their relative positions on one side of an insulated supporting card 3, so that they may be handled as a unit in their assembled form. For this purpose I prefer to use a card or pad of fibrous material, such as 80 asbestos, for the reason that mica is quite expensive and when constantly subjected to high temperatures has a tendency to disintegrate. By coating the pad and impregnating the same more or less with an earthy 85 material or filler of the nature of an insulating compound 4 it permits the use of a much poorer grade of asbestos or other fibrous material than would otherwise be possible if the winding and pad were placed 90 in direct contact. The insulating compound 4 is preferably placed on both surfaces of the porous pad and at least partially impregnates it and makes a smooth, firm surface against which the heating element may 95 be pressed, thereby making a positive insulation which does not injure the wire and still leaves the card flexible. A suitable compound for this purpose is a mixture of 100 silica and a binder.

105 The connection of the heating element to

the supporting pad 3 is made at the terminal ends of the windings. This connection includes an eyelet 5 secured to the asbestos pad 3 previous to its being coated with the insulating compound 4. A second and longer eyelet 6 together with the adjacent ends of the ribbons 1, extends through the first eyelet 5 as shown in Fig. 4. A washer 7 is placed over the upper end of the eyelet 5 and the ends of said ribbons extend above it and are held thereagainst by said eyelet 6. The eyelet 6 is crimped, swaged or headed so as to secure all the parts firmly together, thereby gripping the cards 2 and 3 firmly between the washer 7 and the flange 6' of the eyelet 6. A flat headed screw 8 extends through the eyelet 6 and has a nut 9 firmly screwed down thereon so as to further secure the connection. With the windings so attached to the supporting card 3 they may be conveniently handled for the purpose of assembling, dismantling or for transportation. In order to use this heating element, it is, of course, necessary to have a suitable housing within which it is to be mounted, which housing constitutes the electrically heated device. In the specific embodiment herein illustrated this housing is shown in the form of a flat iron comprising a heating plate 10 having a polished surface 11 and a protecting casing 12 secured to the plate 10. The inner face of the heating plate 10 is recessed at a uniform depth nearly coextensive with the area of the plate, and the recess is filled with an insulating compound 13, preferably spread in the recess in a semi-fluid or plastic condition, and then allowed to solidify. The heating element rests directly upon this insulating compound 13 and is forced into firm contact therewith by means of the pressure plate 14.

The clamping means for securing the pressure plate 14 in position includes a bolt or screw 15, secured to the boss 16 on the heating plate 10, and extending upwardly through the plate 14 to permit the nut 17 to be screwed down against the plate 14. The bolt 15 extends to the exterior of the casing 12 to permit the nut 18 to be screwed thereon for clamping the casing 12 to the plate 10.

The electric conductors 19 are led into the housing in any suitable manner so as to be connected to the screws 8, which also serve as binding posts. In the embodiment herein shown, the conductors enter at the rear of the handle 20 through a tubular extension 21 and pass down through the support 22. The ends of the conductor wires are looped 60 and passed over the screws 8 above the nuts 9 and secured thereto by means of the nuts 23.

Although but one specific embodiment of this invention has been herein shown and described, it will be understood that numerous details of the construction shown may

be altered or omitted without departing from the spirit of this invention as defined by the following claims.

I claim:

1. In a device of the class described, a heating plate, a pressure plate, a heating element between them, and insulation between said heating element and one of said plates, said insulation comprising a pad of soft fibrous material containing and coated with earthy insulating filler material on the side adjacent to the heating element. 70

2. In a device of the class described, a heating plate, a pressure plate, a heating element between them, and insulation between said heating element and one of said plates, said insulation comprising a pad of light asbestos impregnated and coated with earthy insulating filler material. 80

3. An electric heating device, comprising a metallic heating plate having its back side coated with a layer of insulating compound, an electric heating element behind said coated side, a pressure plate behind said heating element, a fibrous flexible pad impregnated with earthy material and interposed between said heating element and said pressure plate and means for holding said pressure plate and heating plate in clamping engagement with said heating 95 element and pad. 90

4. An electric heating device, comprising a flat heating plate coated on one side with a layer of insulating compound, a flat electric element lying against said coated side of said plate, a pressure plate behind said heating element, a thin flexible pad of porous insulating material interposed between said pressure plate and heating element, said porous pad being coated and at least 105 partially impregnated with insulating earthy matter, and means for holding said pressure plate and heating plate in clamping engagement with said heating element. 100

5. In a device of the class described, a heating plate, a pressure plate, a heating element between them, and insulation between said heating element and both of said plates, the insulation between said pressure plate and heating element comprising a pad of soft fibrous heat insulating material coated and impregnated with earthy insulating 115 filler material on the side adjacent to said heating element, and the insulation between said heating plate and said heating element comprising a coating of hard-set earthy material on said heating plate. 120

6. In an electric heater, the combination of a heating plate, a pressure plate, a heating element interposed between said plates, a hollow casing surrounding said pressure plate and heating element and coating with said heating plate to form a housing therefor, and a single stud bolt having a pair of nuts thereon, one being adapted to secure 130

said casing in position on said heating plate, and the other being adapted to draw said pressure plate and heating plate into clamping engagement with the heating element, said heating plate and casing being formed and adapted for coengagement to prevent relative turning on said stud.

7. In a device of the class described, a body element adapted for the reception and transmission of heat, in combination with a heat generating and distributing element comprising a plurality of small electric conductors of low conductivity and disposed in distributed relation within said body and

connected together at each end substantially 15 integrally parallel for electrically heating said body, each connection comprising inner and outer concentric bushings adapted and arranged for holding the terminals rigidly clamped therebetween, and a terminal stud adapted to be secured rigidly in said bushings.

Signed at Detroit this 7th day of September, 1912.

CHARLES P. MADSEN.
